Primary Examiner — Sandra Snapp

(74) Attorney, Agent, or Firm — Thorpe North & Western LLP(57) CLAIM

The ornamental design for the screw top air freshener, as shown and described.

DESCRIPTION

FIG. 1 is a top perspective view of the screw top air freshener in accordance with my invention;

FIG. 2 is a bottom perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left side elevation view thereof; and,

FIG. 8 is a right side elevation view thereof.

The broken lines shown in FIGS. 5-8 are for illustrative purposes only and form no part of the claimed design.
